U.S. Cl. D6—47

FIG. 1

FIG. 2

FIG. 3

FIG. 4

FIG. 5

FIG. 6

FIG. 7

FIG. 8

FIG. 9

FIG. 1 is a top plan view of a seat, embodying my new design;

FIG. 2 is a side elevational view thereof;

FIG. 3 is a front elevational view thereof;

FIG. 4 is a rear elevational view thereof;

FIG. 5 is a bottom plan view thereof;

FIG. 6 is a front perspective downwardly directed view of a first embodiment of the seat of FIG. 1;

FIG. 7 is a rear perspective view of the seat of FIG. 6;

FIG. 8 is a front perspective, downwardly directed view of a second embodiment of the seat of FIG. 1; and

FIG. 9 is a rear perspective view of the seat of FIG. 8.

I claim:

The ornamental design for a seat as shown.
